UNITED STATES PATENT OFFICE.

RUDOLPH KRETER, OF NEW YORK, N. Y., ASSIGNOR TO GEORGE STECK,
OF SAME PLACE.

MUSIC-RACK FOR PIANOS.

SPECIFICATION forming part of Letters Patent No. 248,477, dated October 18, 1881.

Application filed July 16, 1881. (No model.)

To all whom it may concern:

Be it known that I, RUDOLPH KRETER, of New York, in the State of New York, have invented a new and useful Improvement in Music-Racks for Upright Piano-Fortes and Organs, of which the following is a specification.

In the accompanying drawings, Figure I represents a front view of part of the front of an upright piano, showing the position of the music-rack. Fig. II is a cross-section of the same. Fig. III is a cross-section showing the music-rack extended for supporting the music book or sheet.

Similar letters represent similar parts in all the figures.

A represents part of the front of an upright piano, and B the music-rack fitted into a suitable square or oblong opening made in said front A.

To the lower end of the rack B, some little distance from its bottom, one or more links, C, are hinged to the back of said rack, the other ends of which said links are hinged, at a, to the inner side of the piano-front A, in a line with the bottom edge of the opening in said front A.

D is a spring attached to the inner side of the piano-front A, acting against the links C.

The upper part of the music-rack is allowed to slide freely in the opening of the piano-front and is guided by a suitable guide, E, acting against the back of the music-rack B and attached to the inside of the piano-front.

Near the upper end of the rack B, at the sides, 35 projections or stop-pins n are provided, and at the sides of the opening, on the inside of the piano-front A, projections m are attached, upon which the pins n will rest when the music rack B is pulled out and extended ready to receive the music, to stop the downward motion of said rack and to support the same.

Near the bottom of the music-rack B an elongated projection, F, is provided to support the music book or sheet.

When the music-rack is not in use, and in a position shown in Fig. II, the guide E will support and press the upper part of the rack close to the inside of the piano-front A, and the spring

D will act against the link C close to its hinge a, keeping thereby the lower part of the music-rack in position, and said music-rack B will have the appearance of a countersunk panel in the piano-front A.

When the music-rack is to be used, its lower end is pulled out, when the link C will guide and cause the same to move downward until the pins n come in contact with the fixed projections m. The spring D will then act against the bottom edge of the link C, and thus keep the music-rack steady and in position. To move the music-rack back again the same must be partly moved upward when the action of the link C will guide the same into its proper place.

When the link C is made of some thickness 65 the top edge or top surface of the same will form a brace to hold the rack in its desired downward position, and the pins n and fixed projections m may be dispensed with; but I prefer the use and an arrangement of these 70 pins n and projections m as greater security for holding and supporting the music-rack when moved outward and downward to support the music. It will be perceived that with this arrangement greater height of music-rack 75 surface is obtained than the height or depth of the opening necessary for the action of the sliding rack, and all appearance of hinges on the face of the piano-front is obviated.

What I claim as my invention, and desire to 80 secure by Letters Patent, is—

In the front of an upright piano or organ, a music-rack, B, the upper part of which is free to move in a suitable opening in said piano-front and hinged near its lower end to a link 85 or links, C, hinged to the inside of the piano-front, in combination with spring D and guide E, and with or without projecting stop-pins n and fixed projections m, the whole being arranged to operate substantially in the manner 90 and for the purpose described.

RUDOLPH KRETER.
